CONDUIT CAP

Ralph G. Whitlock, Los Angeles, and Lewis Sharp, Huntington Park, Calif., assignors to Federal Foundation, Inc., Las Vegas, Nev., a corporation of Nevada

Application March 7, 1934, Serial No. 714,538

15 Claims. (Cl. 221—100)

Our invention relates to closures for containers, and more particularly to a locking cap for the inlet conduit of a gasoline storage tank such as used by service stations.

5 The practice of "night dumping", often followed by dishonest service station owners and operators, is the filling of gasoline storage tanks with cheap gasoline of low quality, this being sold at a high price and dispensed through a pump bearing the brand of a high quality product. In a like manner the high quality gasoline contained in such storage tanks is often blended with a quantity of low quality fuel and sold at a high price.

10 An object of our invention is to provide a conduit cap which registers the number of times the cap is opened so that surreptitious access to a storage tank conduit cannot be had without leaving evidence thereof.

15 Other objects and advantages will be made manifest in the following description taken in connection with the accompanying drawings, in which:

Fig. 1 is a semi-diagrammatic, vertical sectional view showing the device of our invention in its relation to a storage tank.

Fig. 2 is an enlarged plan view of the device shown in Fig. 1, the cover being open to disclose the parts therebeneath.

30 Fig. 3 is a fragmentary view similar to Fig. 2 showing the operation of certain parts disclosed therein.

Figs. 4 and 5 are fragmentary, vertical sectional views taken on the lines 4—4 and 5—5 of Fig. 2.

Figs. 6 and 7 are vertical sectional views taken on the lines 6—6 and 7—7 of Fig. 2.

Fig. 8 is a horizontal sectional view taken on the line 8—8 of Fig. 6.

40 Figs. 9 and 10 are fragmentary views similar to Fig. 8 showing the successive operative positions of the parts disclosed therein.

Fig. 11 is a vertical sectional view of a gauge stick for use with the storage tank shown in Fig. 1.

Fig. 12 is a horizontal sectional view taken on the line 12—12 of Fig. 11.

Fig. 13 is an enlarged diagrammatic view of a portion of the device shown in Fig. 4.

50 Fig. 14 is a vertical sectional view taken on the line 14—14 of Fig. 13.

Fig. 15 is a view similar to Fig. 13 showing another position of the parts disclosed therein.

Referring specifically to the drawings, and particularly to Figs. 2 and 6, a conduit cap 10 of our

invention includes a conduit 11, an outer housing 12, an inner housing 13, and a locking and registering mechanism 14.

The conduit 11 extends upward from an underground storage tank 20 into a suitable pit as shown in Fig. 1. Screwed onto the upper end of the conduit 11 as shown in Fig. 6 is a cap 22 having a short tube 23 fixed to the underside thereof, the purpose of which will be made clear hereinafter.

The outer housing 12 is cast of metal to provide a vertical wall 25, a bottom 26, and a central tubular member 27, the wall 25 being formed to provide a shoulder 28 at its upper edge. Cast integral with the housing 12 is a 15 pair of outward extending apertured ears 29 and an apertured lug 30. The tubular member 27 of the housing 12 is reduced in diameter at its upper end to provide a shoulder 32. The housing 12 is fixed to the upper end of the conduit 11 as shown in Fig. 6 by a set screw 33, the latter being threaded into the wall of the tubular member 27.

Hinged to the ears 29 of the housing 12 by a hinge pin 34 is an outer cover 35 having a 25 gasket 36 on the underside thereof. Mounted on a suitable lug 37 on the cover 35 is a clamp latch 38 as shown in Figs. 1 and 2. The latch 38 normally engages the lug 30 so as to firmly press the cover 35 onto the upper edge of the housing 12, the cover 35 being locked to the housing 12 by a padlock inserted through the apertured lug 30. Formed integral with the cover 35 adjacent the pivot thereof is a bifurcated arm 40, the ends of the latter being pinned to a depending rod 41. The lower end of the rod 41 is operatively connected to the stem 42 of a shut-off cock 43, the latter being mounted in a delivery pipe 44 of the storage tank 20 as shown in Fig. 1. Fixed to the side wall 25 of the housing 12 is a housing 45 enclosing the rod 41 and the mechanism attached thereto.

The inner housing 13 includes a cast receptacle 50 formed to provide a bottom 51, side walls 52 and a tubular central member 53 as 45 shown in Fig. 6. Formed integral with the receptacle 50 at each corner thereof is an apertured boss 54. The receptacle 50 normally rests on the shoulder 32 of the member 27 of the housing 12. The upper side of the receptacle 50 is closed by a deck plate 55, the periphery of the latter resting on a suitable gasket 56 on the shoulder 28 of the housing 12. Formed at each corner of the deck plate 55, at each corner thereof, is a threaded boss 57, the latter 55

being aligned with the bosses 54 of the receptacle 50, the deck plate 55 being secured to the receptacle 50 by suitable screws 58 which extend upward through the bosses 54 into threaded engagement with the bosses 57. The receptacle 50 and deck plate 55 thereof are fixed as a unit within the housing 12 by a ring nut 60, the latter being screwed onto the upper end of the tubular member 27 of the housing 12 as shown in Figs. 3 and 6.

Mounted on the deck plate 55 as shown in Fig. 6 is a combination lock 62 having a dial 63, the latter extending upward through a suitable opening in the plate 55, the dial being normally covered by a removable cap 64. The lock 62 has a keeper 65 extending through the tubular member 53 of the receptacle 50 into a suitable slot in the tubular member 27 of the housing 12, as shown in Fig. 6. Fixed to the underside of the deck plate 55 alongside the lock 62 is a counter 66 operatively connected to the keeper 65 of the lock 62 by an arm 67 as shown in Fig. 8. The counter 66 is visible from above the plate 55 through a suitable window shown in Fig. 2.

Mounted on the upper side of the deck plate 55, as shown in Figs. 2, 4, and 5, is a pair of semicircular aligned housings 68 and 69 in which an inner cover 70 is pivotally mounted, the latter normally preventing access to the cap 22 of the conduit 11 as shown in Fig. 6. Pressed into the cover 70 on the pivotal axis thereof is a shaft 71, the ends of the latter extending into the housings 68 and 69. Keyed to the end of the shaft 71 within the housing 68 is a ratchet wheel 73, the lower portion of which extends through a suitable opening in the deck plate 55 into the receptacle 50. Rotatably mounted on the shaft 71 adjacent the ratchet wheel 73 is a segmental plate 74 as shown in Fig. 13. The plate 74 has a pair of flanges 75 and 76 extending over and conforming with the periphery of the ratchet wheel 73, these flanges being separated by an opening 77. Fixed to one side of the ratchet wheel 73 is a pin 78 for operating the plate 74 in a manner to be described hereinafter. Fixed to the underside of the plate 55, as by screws 80, is a pair of spring pawls 81 and 82 mounted in radial alignment with the ratchet wheel 73.

Keyed on the end of the shaft 71 within the housing 69 is a gear wheel 85, the lower portion of the latter extending through a suitable opening in the deck plate 55 as shown in Fig. 7.

Mounted on the underside of the deck plate 55 below the semicircular housing 69 is an L-shaped plate 90, there being an L-shaped slideway 91 formed on the underside of the plate 55 above the plate 90 as shown in Figs. 7, 8, and 5. Formed integral with and extending downward from the plate 90 through a suitable opening provided in the bottom 51 of the receptacle 50 is a cylindrical magazine 93 having a nut 94 threaded on the lower end thereof. Within the magazine 93 is a plurality of annular tokens 96, these being urged upward into the slideway 91 of the plate 55 by a compression spring 97, a relatively thick disc 98 being interposed between the spring 97 and the lowermost of the stack of tokens 96.

Formed through the deck plate 55 in vertical alignment with one end of the slideway 91 is an opening 99 as shown in Fig. 3, this opening being normally closed by a pivoted cover 100. Slidable in the slideway 91 between the L-shaped plate 90 and the deck plate 55 is a plunger 102, the latter being formed to provide teeth 103, as

shown in Fig. 7, for engagement with the aforementioned gear wheel 85. Fixed to the underside of the plunger 102 and extending downward through suitable slots 104 and 105 provided in the plate 90 are lugs 106 and 107 as shown in Fig. 8.

Slidable on the underside of the deck plate 55 beside the plate 90 is a bar 110, one end of the latter having a pin 111 thereon while the opposite end 112 of the bar 110 normally extends into the slideway 91 as viewed through the opening 99 of the plate 55 in Fig. 2. Fixed centrally on the bar 110 is a stop lug 113 positioned to contact a block 114 as shown in Fig. 10. The bar 110 is normally urged leftward as viewed in Fig. 8 by a spring 115. Pivoted on the underside of the plate 90 is a lever 118, one end of the latter being slotted to receive the pin 111 of the bar 110 while the other end rests against the lug 106 of the plunger 102.

Screwed to the underside of the plate 90 in close proximity with the magazine 93 is a lock 117, there being a keyhole 118 through the plate 55 in alignment with the lock 117 as shown in Fig. 3. Extending horizontally from the lock 117 is an arm 119 having a downward extending pin 120 provided thereon. The extremity of the arm 119 is normally held in the path of the lug 107 of the plunger 102 by a spring 121 as seen in Fig. 8.

Mounted on the underside of the deck plate 55 beside the aforementioned counter 66 is a second counter 125 operated by a link 126. The end of the link 126 opposite the counter 125 is slotted to receive the aforementioned pin 120 of the arm 119 of the lock 117. As shown in Fig. 8, the slotted end of the link 126 is notched to receive the lug 107 of the plunger 102, the link being urged into contact with the lug 107 by an extension spring 128.

Operation

The conduit cap 10 of our invention normally appears as shown in Fig. 1 with the cover 35 locked to the housing 12. To gain access to the mouth of the conduit 11 for the purpose of supplying the storage tank with gasoline the padlock is removed and the latch 38 disengaged from the lug 30, thus permitting the cover 35 to be opened to the position in which it is shown in Figures 2 and 4. As the cover 35 is opened, the arm 40 thereof raises the rod 41 so as to rotate the stem 42 and shut the cock 43, thus prohibiting the pumping of any gasoline from the tank 20 during the filling operation.

It will be noted in Fig. 8 that one of the tokens 96, hereinafter designated at 96a, is positioned in the slideway 91 midway between the magazine 93 and the opening 99 at the end of the slideway 91, it being also noted that a portion of the token 96a is disposed so as to shut off the keyhole 118 from the lock 117.

After opening the outer cover 35, the inner cover 70 is raised a relatively small amount. This causes the gear wheel 85 to rotate and the plunger 102 is moved from the position shown in Fig. 8 to the position in which it is shown in Fig. 9, it being noted that further movement of the cover 70 is prevented by engagement of the lug 107 with the end of the lock arm 119. During this initial movement of the plunger 102 the link 126 is pushed so as to actuate the counter 125 and at the same time the bar 110 is moved by the lever 118 so that the end 112 of the bar 110 is withdrawn from the slideway 75

as shown in Fig. 9. As the plunger 102 startsward therefrom. Hinged to the lower end of the pipe 133 is a swinging shut-off valve 134 normally urged to closed position by a torsion spring 135. Slidable within the pipe 133 is a gauge stick 136 formed of metal angle bars 137 and wooden segments 138 as shown in Fig. 12. The valve 134 is forced open by the stick 136 when desirable to gauge the contents of the tank 20 and swings shut when the gauge stick is removed so as to prevent surreptitious filling of the tank 20 through the pipe 133.

Although we have shown and described but one form of our invention, it is to be understood that various changes and modifications might be made therein without departing from the spirit of the invention or the scope of the appended claims.

We claim as our invention:

1. In a conduit cap the combination of: a fill pipe; a head on said pipe; a pipe closure member movably mounted on said head and having a position closing said pipe and a position freeing said pipe to permit access thereto; and means operated by movement of said closure and provided on said head for discharging a token for each cycle of actuation of said member to permit access to said fill pipe.

2. In a conduit cap the combination of: a fill pipe; a head on said pipe; a pipe closure member movably mounted on said head and having a position closing said pipe and a position freeing said pipe to permit access thereto; a magazine for tokens provided on said head; and means connected with said member for discharging a token from said magazine for each actuation of said member to permit access to said fill pipe.

3. In a conduit cap the combination of: a fill pipe; a head on said pipe; a pipe closure member movably mounted on said head and having a position closing said pipe and a position freeing said pipe to permit access thereto; means preventing reversal of direction of movement of said closure member either during an opening movement or a closing movement thereof; a counter actuated by said member counting the number of cycles of operation performed by said closure member; a magazine for tokens provided on said head; and means connected with said member for discharging a token from said magazine for each actuation of said member to permit access to said fill pipe.

4. In a conduit cap the combination of: a fill pipe; a head on said pipe; a pipe closure member movably mounted on said head and having a position closing said pipe and a position freeing said pipe to permit access thereto; means preventing reversal of direction of movement of said closure member during an opening movement thereof or a closing movement thereof; lock means for locking said closure member in closed position; a token magazine on said head, said lock means permitting an initial opening movement of said closure member and said non-reverse means holding said closure member thus partially open; and means provided on said head and actuated by said closure member in each complete opening and closing operation to position a token in sealing relation with said lock means, said token positioning means feeding said token away from sealing relation with said lock means incidental to said initial opening movement of said closure member, said token feeding means, after the unlocking of said lock means, being actuated

The cap 22 is now removed from the conduit 11 and the tank 20 filled in the usual manner. After filling the tank 20 the cap 22 is replaced and the token 96a is removed from the slideway 91 through the opening 99 by a suitable instrument (not shown) provided therefor. The inner cover 70 is then closed and the mechanism 14 returns to the position as shown in Fig. 8. Due to the fact that the end 112 of the bar 111 must enter the space occupied by the token 96a in Fig. 10 when the cover 70 is closed, it is necessary to remove this token before being able to close the cover 70.

When the cover 70 is fully opened the ratchet wheel 73 is rotated to the position shown in Fig. 15, the pin 78 thereon slightly rotating the segmental plate 75 causing the pawl 81 to be pushed out of engagement with the ratchet and allowing the pawl 82 to move into engagement with the ratchet wheel, thus preventing the opening of the cover 70 after starting to close the same. As the inner cover 70 is closed the lock arm 113 swings into the path of the lug 107 as shown in Fig. 8. The outer cover 35 is now closed and locked and the absence of the token 96a in the conduit cap 10 denotes that access has been had to the mouth of the conduit 11. A blank form is then filled out by the station operator and signed by the operator and tank truck driver stating the number of gallons supplied to the storage tank, the time the same was supplied, etc.

Referring now to Fig. 11, we have shown therein a novel form of gauge device 130 to be used on the storage tank 20. The device 130 includes a pipe 131 which extends from the tank 20 to the surface of the ground thereabove. Screwed onto the upper end of the pipe 131 is a cap 132 having a pipe 133 extending down-

Although we have shown and described but one form of our invention, it is to be understood that various changes and modifications might be made therein without departing from the spirit of the invention or the scope of the appended claims.

We claim as our invention:

1. In a conduit cap the combination of: a fill pipe; a head on said pipe; a pipe closure member movably mounted on said head and having a position closing said pipe and a position freeing said pipe to permit access thereto; and means operated by movement of said closure and provided on said head for discharging a token for each cycle of actuation of said member to permit access to said fill pipe.

2. In a conduit cap the combination of: a fill pipe; a head on said pipe; a pipe closure member movably mounted on said head and having a position closing said pipe and a position freeing said pipe to permit access thereto; a magazine for tokens provided on said head; and means connected with said member for discharging a token from said magazine for each actuation of said member to permit access to said fill pipe.

3. In a conduit cap the combination of: a fill pipe; a head on said pipe; a pipe closure member movably mounted on said head and having a position closing said pipe and a position freeing said pipe to permit access thereto; means preventing reversal of direction of movement of said closure member either during an opening movement or a closing movement thereof; a counter actuated by said member counting the number of cycles of operation performed by said closure member; a magazine for tokens provided on said head; and means connected with said member for discharging a token from said magazine for each actuation of said member to permit access to said fill pipe.

4. In a conduit cap the combination of: a fill pipe; a head on said pipe; a pipe closure member movably mounted on said head and having a position closing said pipe and a position freeing said pipe to permit access thereto; means preventing reversal of direction of movement of said closure member during an opening movement thereof or a closing movement thereof; lock means for locking said closure member in closed position; a token magazine on said head, said lock means permitting an initial opening movement of said closure member and said non-reverse means holding said closure member thus partially open; and means provided on said head and actuated by said closure member in each complete opening and closing operation to position a token in sealing relation with said lock means, said token positioning means feeding said token away from sealing relation with said lock means incidental to said initial opening movement of said closure member, said token feeding means, after the unlocking of said lock means, being actuated

Although we have shown and described but one form of our invention, it is to be understood that various changes and modifications might be made therein without departing from the spirit of the invention or the scope of the appended claims.

We claim as our invention:

1. In a conduit cap the combination of: a fill pipe; a head on said pipe; a pipe closure member movably mounted on said head and having a position closing said pipe and a position freeing said pipe to permit access thereto; and means operated by movement of said closure and provided on said head for discharging a token for each cycle of actuation of said member to permit access to said fill pipe.

2. In a conduit cap the combination of: a fill pipe; a head on said pipe; a pipe closure member movably mounted on said head and having a position closing said pipe and a position freeing said pipe to permit access thereto; a magazine for tokens provided on said head; and means connected with said member for discharging a token from said magazine for each actuation of said member to permit access to said fill pipe.

3. In a conduit cap the combination of: a fill pipe; a head on said pipe; a pipe closure member movably mounted on said head and having a position closing said pipe and a position freeing said pipe to permit access thereto; means preventing reversal of direction of movement of said closure member either during an opening movement or a closing movement thereof; a counter actuated by said member counting the number of cycles of operation performed by said closure member; a magazine for tokens provided on said head; and means connected with said member for discharging a token from said magazine for each actuation of said member to permit access to said fill pipe.

4. In a conduit cap the combination of: a fill pipe; a head on said pipe; a pipe closure member movably mounted on said head and having a position closing said pipe and a position freeing said pipe to permit access thereto; means preventing reversal of direction of movement of said closure member during an opening movement thereof or a closing movement thereof; lock means for locking said closure member in closed position; a token magazine on said head, said lock means permitting an initial opening movement of said closure member and said non-reverse means holding said closure member thus partially open; and means provided on said head and actuated by said closure member in each complete opening and closing operation to position a token in sealing relation with said lock means, said token positioning means feeding said token away from sealing relation with said lock means incidental to said initial opening movement of said closure member, said token feeding means, after the unlocking of said lock means, being actuated

by further movement of said closure member to discharge said token from said cap into a position where it may be taken up by the operator.

5. In a conduit cap the combination of: a head having an inlet passage; an outer cover for said head which covers said passage when closed; an inner cover for said passage, said inner cover preventing the closing of said outer cover when said inner cover has been opened to a certain minimum open position in which said inner cover still prevents access to said inlet passage; means preventing the closing of said inner cover after it has been opened to its minimum position until it has been entirely opened to permit access to said inlet passage; and means actuated by said inner cover during each cycle of opening and closing to deliver a token into a position where it may be taken up 10 by the operator.
6. In a conduit cap the combination of: a housing on said conduit; a cover on said housing to close the mouth of said conduit; a lock within said housing to lock said cover over the mouth of said conduit, said cover being slightly movable while in locked position; a token magazine in said housing; means for conveying a token from said magazine to said lock, said token being normally disposed to prevent actuation of said lock; means responsive to a slight movement of said door to shift said token to permit actuation of said lock; and means responsive to further movement of said door to further move said token to permit removal of 25 said token from said housing.

7. A combination as in claim 6 in which ratchet means is provided to prevent closing said door after starting to open it until said door is entirely opened.

8. A combination as in claim 6 in which ratchet means is provided to prevent closing said door after starting to open it until said door is entirely opened, said ratchet means also preventing opening said door after starting to close it until said door is entirely closed.

9. A combination as in claim 6 in which a plurality of tokens is provided in said magazine, each of said tokens being individually marked to distinguish it from the others.

10. In a conduit cap the combination of: a housing on said conduit; a cover on said housing to close the mouth of said conduit; a key lock within said housing to lock said cover over the mouth of said conduit, said cover being slightly movable while in locked position, said housing having a keyhole in a wall thereof to permit insertion of a key into said lock; a token magazine within said housing; a token slideway extending from said magazine to a point between said lock and said housing, one of said tokens being normally positioned in said slideway between said lock and the upper wall of said housing, said keyhole being shut off from said lock by said token; means responsive to a slight movement of said door to shift said token in said slideway to permit insertion of a key into

said lock to unlock said cover; and means responsive to the closing of said door to shift a successive token into position to shut off said keyhole from said lock, said successive token forcing said first mentioned token into position to permit removal thereof from said housing.

11. A combination as in claim 2 in which means is provided to prevent the closing of said cover until said token is removed from said housing.

12. In a conduit cap the combination of: a head having an inlet passage; a cover for said passage, said cover having movement on said head between passage closing and passage opening positions; a lock for locking said cover against being moved more than a relatively small distance from said passage closing position to a partially opened position in which said cover still denies access to said passage; means operatively connected to said cover for preventing access to said lock when said cover is in completely closed position, said means being actuated by said cover to permit access to said lock when said cover has been moved to said partially open position; and means automatically preventing the return of said cover from partially open position to closed position until said cover has been entirely opened.

13. In a conduit cap the combination of: a head having an inlet passage; a cover for said passage, said cover having movement on said head between passage closing and passage opening positions; a lock for locking said cover against being moved more than a relatively small distance from said passage closing position to a partially opened position in which said cover still denies access to said passage; means operatively connected to said cover for preventing access to said lock when said cover is in completely closed position, said means being actuated by said cover to permit access to said lock when said cover has been moved to said partially open position; a counter; and means for actuating said counter each time said cover is moved from closed position to said partially open position.

14. In a gasoline storage system, the combination of: a closed storage reservoir having an upper wall; means for discharging liquid into said reservoir; means for removing liquid from said reservoir; a pipe tightly fitted into said upper wall and extending downward into said reservoir; a liquid trap on the lower end of said pipe; yieldable means for closing said trap excepting when a relatively strong pressure is exerted downwardly thereagainst; and a measuring stick disposed in said pipe and adapted to force said trap open and extend into said reservoir, and then be withdrawn therefrom to measure the contents of said reservoir.

15. A combination as in claim 2 in which means is provided for preventing a complete cycle of operation of said pipe closure member when the supply of tokens in said magazine is exhausted.

RALPH G. WHITLOCK. 65
LEWIS SHARP.
